J. Maynardier.

UNITED STATES PATENT OFFICE.

BENJAMIN J. GREELY, OF BOSTON, MASSACHUSETTS.

STOPPER-EXTRACTOR.

SPECIFICATION forming part of Letters Patent No. 379,010, dated March 6, 1888.

Application filed September 3, 1887. Serial No. 248,736. (No model.)

To all whom it may concern:

Be it known that I, BENJAMIN J. GREELY, of Boston, in the county of Suffolk and State of Massachusetts, have invented a new and useful Stopper-Extractor, of which the following is a specification, reference being had to the accompanying drawings, in which—

Figure 1 is a central vertical section of a portion of a corked bottle with my new extractor in place. Fig. 2 is a section on line 2 of Fig.

1. Figs. 3 and 4 are views of my new extractor.

My new cork-extractor is an improvement upon extractors of the kind shown in Loffler's patent, No. 59,241, dated October 30, 1866, and Englesdorff's patent, No. 172,104, dated January 11, 1876; and my invention consists of a piece of metal having a lengthwise groove and at one end a sidewise extension, the lengthwise groove forming a passage for the escape of air and gas from the bottle, whereby the cork is not only more easily pulled, but the pent-up air or gas is given a chance to escape, thus obviating the annoyance now caused by the popping and spurting in opening champagne, cider, and the like.

My extractor is best made of a piece of wire, a , one end of which is bent to form a sidewise extension, a' , which is preferably flattened, as shown. The air-passage consists in a lengthwise groove, b , in the wire, the groove being preferably a straight groove opposite the extension a' , as shown.

My extractor is provided with a handle, a^2 ,

made in various ways too obvious to need description.

When the extractor is used, the end of extension a' is inserted between the cork and the neck of the bottle, and is then forced below the inner end of the stopper and turned to engage the stopper. A slight pull is then sufficient to start the stopper, the air or gas rapidly escaping as soon as the bottom of the groove is passed beyond the inner end of the stopper. It is very important that the air-passage should be a groove in the extractor, because it is thereby readily cleaned out if clogged and is not readily clogged. In those extractors in which the air-passage is a bore through the extractor the passage is frequently clogged, and is cleaned out when clogged with considerable difficulty. Groove b is preferably diametrically opposite the sidewise extension a' , so that when the extension is turned to engage the inner end of the stopper the inner surface of the neck of the bottle forms a portion of the wall of the air-passage.

What I claim is—

The improved stopper-extractor herein described, made of a piece of metal, a , having a lengthwise groove, b , in the surface of the extractor, and at one end a sidewise extension, a' , substantially as and for the purpose set forth.

BENJAMIN J. GREELY.
